(57) **CLAIM**

The ornamental design for a handle for a loudspeaker, as shown and described.

DESCRIPTION

FIG. 1 is a perspective view of a handle for a loudspeaker showing my new design;

FIG. 2 is an elevational view thereof; and,

FIG. 3 is a cross-sectional view taken along line 3-3 in FIG. 2. The broken line showings form no part of the claimed design.

1 Claim, 3 Drawing Sheets

FIG. 1

FIG. 2

FIG. 3
